Primary Examiner—Alan P. Douglas*Assistant Examiner*—Robert M. Spear*Attorney, Agent, or Firm*—Owen J. Meegan; Aubrey C. Brine; Donal B. Tobin[57] **CLAIM**

The ornamental design for a hood for a dispenser, as shown and described.

DESCRIPTION

FIG. 1 is a top plan view of a hood for a dispenser showing my new design;

FIG. 2 is a front elevational view thereof;

FIG. 3 is a bottom plan view thereof;

FIG. 4 is a left side elevational view thereof, the right side elevational view being a mirror image thereof; and,

FIG. 5 is a rear elevational view thereof.
